CLAIM

I claim the ornamental design for a luggage box for a vehicle roof, as shown and described.

DESCRIPTION

FIG. 1 is a top view of a luggage box for a vehicle roof; FIG. 2 is a bottom view of the luggage box for a vehicle roof of FIG. 1;

FIG. 3 is a right-side view of the luggage box for a vehicle roof of FIG. 1;

FIG. 4 is a left-side view of the luggage box for a vehicle roof of FIG. 1;

FIG. 5 is a front view of the luggage box for a vehicle roof of FIG. 1;

FIG. 6 is a rear view of the luggage box for a vehicle roof of FIG. 1; and,

FIG. 7 is a perspective view of the luggage box for a vehicle roof of FIG. 1.

The figures include broken lines that are directed to environment and are for illustrative purposes only; the broken lines form no part of the claimed design.

1 Claim, 7 Drawing Sheets
